TOY JET PROPELLED BOAT

Demetrios Theodosis, 2177 31st St.,
New York, N.Y. 11105

Filed Aug. 22, 1973, Ser. No. 390,547

Term of patent 14 years

Int. Cl. D21—01

U.S. Cl. D34—15 JJ

FIG. 1 is a side elevational view of a toy jet propelled boat showing my new design;

FIG. 2 is a top plan view thereof;

FIG. 3 is a bottom plan view thereof;

FIG. 4 is a front elevational view thereof; and

FIG. 5 is a rear elevational view thereof.

I claim:

The ornamental design for a toy jet propelled boat, substantially as shown.
